UNITED STATES PATENT OFFICE

PATRICK J. MADDEN, OF CHICAGO, ILLINOIS.

PLUMBING-FIXTURE.

981,941.

Specification of Letters Patent. Patented Aug. 24, 1909.

Application filed May 24, 1906, Serial No. 318,513. Renewed June 5, 1909. Serial No. 600,405.

To all whom it may concern:

Be it known that I, PATRICK J. MADDEN, a citizen of the United States, residing at Chicago, in the county of Cook and State of Illinois, have invented certain new and useful Improvements in Plumbing-Fixtures, of which the following is a specification:

The term "fixtures" as used in this specification is intended to comprehend water closets, urinals, sinks, bath tubs, wash basins, and all other plumbing devices in the nature of receptacles with which it is necessary to make a pipe connection for either supplying or evacuating the receptacle.

15 In its broadest aspect the invention covers and includes either an inlet or an outlet pipe, and in a more limited aspect it includes a co-operative relation of both, with respect to the bowl.

20 For the sake of brevity, the term "bowl" will hereinafter be used to denote the receptacle of the fixture, but with the understanding that any other specific name for a receptacle of any particular type or character 25 may be read for it.

The invention is particularly well adapted to that class of fixtures in which the bowl has to be removed from time to time for the purpose of removing obstructions or for 30 pair purposes, and with fixtures of this class, especially those in which the bowl must be removed and put in place from "in front" (i. e., without going back of the wall or slab through which the pipe connection 35 or connections extend), facility of removal and replacement is, of course, important.

As before intimated, the invention is applicable to all classes of plumbing fixtures, but my original aim was to provide an 40 proved urinal, and since it is to this class of fixtures that the invention is particularly adapted, I have selected such a fixture for illustrating the invention and will herein-after particularly describe this embodiment 45 of it, with the understanding, however, that excepting as to those features which are peculiar to this class of fixtures the invention includes fixtures of all classes to which it is applicable.

50 The invention consists in the features of novelty that are hereinafter described with reference to the accompanying drawings which are made a part of this specification and in which:

55 Figure 1 is a vertical section of a urinal

embodimenting the invention. Fig. 2 is a front elevation of the lower portion of the bowl.

A represents the bowl (of a urinal) having at top an inlet opening A' and at bottom an outlet opening A''. The bowl shown in the drawings has a vertical back adapted to fit against a wall or slab B, that side of the wall upon which the bowl is located being herein referred to as the front side. The wall has through it two openings B' and B'', through the former of which extends an inlet or supplying pipe C and through the latter of which extends an outlet or discharge pipe D. The outlet pipe D preferably fits the opening B'' snugly so that it is incapable of any vertical movement, while, for reasons that will appear hereinafter clearance is provided between the inlet pipe C and slab B in order to permit limited vertical movement of the inlet pipe in the opening B', and it being understood that the inlet pipe is movable vertically to a limited extent. This vertical movement may be provided for by making the pipe itself of sufficient length to give it the necessary flexibility or by connecting it with a flexible section made of lead. This, however, is a detail which may be left to the discretion of the plumber. The drawings show the several parts of the fixture in their final or 85 ultimate positions, and for the time being the following description will be confined to these relations, a description of the manner of assembling them being given later on.

The bowl has in its rear side a recess or cavity a the top of which slopes downward and rearward so as to provide an inclined shoulder a' and this shoulder rests upon a correspondingly inclined lateral arm of a bracket E which is secured to the wall B by 90 any suitable means. This bracket, in itself, may be sufficient to support the weight of the bowl, and by reason of the inclination of its lateral arm and the corresponding inclination of the shoulder a'' resting upon 95 said arm it will prevent the horizontal movement of the bowl away from the wall B, unless such horizontal movement be accompanied by a sufficient vertical movement to clear the shoulder a' from the arm of the bracket. The vertical movement of the bowl is, however, prevented by means now to be described.

The outlet pipe D has its in-take end deflected downward and upward so as to form 110

what is known in the art as a P-trap, the intake end of which is presented upward and enters the outlet A'' with a snug fit, so as to form a slip-joint therewith. The outlet A'' has a countersink A² so that a groove or channel is left between the bowl and the pipe and this groove is occupied by the upper side of an elastic packing ring or gasket F', the lower side of which occupies a groove in a ring I' carried by a yoke I, the ring and yoke together constituting a follower. The ring I' surrounds the straight vertical portion of the pipe so as to be capable of sliding thereon and the yoke I which is preferably of substantially U-shape, joins the ring I' at diametrically opposite points and straddles the end of the pipe. For the purpose of forcing the follower toward the bowl a screw G engages the yoke at a point directly in line with the extended axis of the vertical end of the pipe, and this screw has threaded engagement with a bracket E' secured to the wall or slab B. With this arrangement it will be seen that by driving the screw home it will react in one direction against the bracket E' and in the other direction against the yoke I and these in turn will tend to force the ring I' toward the bowl and thereby compress the gasket F and form a tight joint between the bowl and the end of the pipe. When the parts are brought to their proper ultimate positions, as shown in the drawing, the shoulder a' will be firmly seated upon the bracket E, whereby downward movement of the bowl is prevented and the horizontal portion of the pipe D will be in contact with the wall B at the top side of the opening B'' thereby preventing any upward movement of the pipe. By reason of the frictional contact of the gasket F with the pipe the downward movement of the bowl is prevented.

The means for connecting the inlet pipe C to the bowl are similar to those just described for connecting the outlet pipe, and similar features of both are represented by similar letters of reference, but for the sake of distinction small letters are used for the parts necessary to the inlet pipe. In order to place the bowl against the wall, it is necessary to lift it high enough to clear the upper extremity of the pipe D. At the same time it is equally necessary that it clear the lower extremity of the inlet pipe C. This being so the normal position of the inlet pipe, must, during the operation of setting the bowl, be somewhat above its normal position when the parts are in their ultimate positions and to this end the opening B' is made large enough to provide clearance above the inlet pipe. The bowl having been put in place and brought to bear upon the bracket E, the screws G and g are driven home, the vertical depending end of the inlet pipe having first been inserted in the

opening A', and the follower rings I and i and gaskets F and f having been put in place on them. The result is that the bowl is clamped between the rings of the followers.

I do not broadly claim in this application: A plumbing fixture having, in combination, a bowl having vertical inlet and outlet openings, horizontal inlet and outlet pipes having their ends bent and presented downwardly and upwardly respectively and registering with said openings, and means for forming a liquid tight joint between the bowl and pipe; nor the means for forming a tight joint between the pipe or pipes and the bowl; nor the means for supporting the bowl, either through the medium of the pipe or pipes or the wall bracket, or all of them; nor the support located opposite the opening in the bowl for supporting the pressure device by which the tight joint is made: All of these things being claimed in my copending application of even date herewith bearing Serial No. 318,512.

What I claim as new and desire to secure by Letters Patent is:

1. In a plumbing fixture, the combination of a bowl having an opening, a pipe, the end of which registers with said opening, a gasket surrounding the pipe and contacting with the bowl, a follower engaging the gasket, a pressure device engaging the follower, means supporting the pressure device and means for resisting the upward movement of the bowl under the influence of the pressure device, substantially as described.

2. In a plumbing fixture, the combination of a bowl having vertical openings at top and bottom, pipes registering with said openings, respectively, gaskets arranged between the bowl and pipes, followers engaging the gaskets, screws engaging the followers, and brackets supporting the screws, substantially as described.

3. In a plumbing fixture, the combination of a bowl having an opening, a pipe, the end of which registers with said opening, a gasket surrounding the pipe and contacting with the bowl, a follower engaging the gasket, a screw engaging the follower, and a bracket supported independently of the bowl, and in turn supporting the screw, substantially as described.

4. In a plumbing fixture, the combination of a bowl having vertical openings at top and bottom, pipes registering with said openings, respectively, gaskets arranged between the bowl and pipes, followers engaging the gaskets, screws engaging the followers, and brackets supported independently of the bowl, and in turn supporting the screws, substantially as described.

5. In a plumbing fixture, the combination of a wall having openings through it, pipes extending through said openings and having

- their ends presented upwardly and downwardly respectively, a bowl having at top and bottom vertical openings with which said pipes register, gaskets arranged between 5 the bowl and pipes, brackets supported by the wall, screws supported by the brackets and means for transmitting pressure from the screws to the gaskets, substantially as described.
10. 6. In a plumbing fixture, the combination of a bowl having an opening, a pipe the end of which extends into said opening, a gasket surrounding the pipe and contacting with the bowl, a follower engaging said gasket, and means for forcing the follower toward the bowl, substantially as described.
7. In a plumbing fixture, the combination of a bowl having an opening, a pipe, the end of which extends into said opening, a gasket 20 surrounding the pipe and contacting with the bowl and pipe, a follower engaging said gasket, said follower having a yoke, and means for engaging the yoke for forcing the follower toward the bowl, substantially as described.
25. 8. In a plumbing fixture, the combination of a bowl having an opening, a pipe, the end of which extends into said opening, a gasket surrounding the pipe and contacting with the bowl, a follower engaging said gasket
- and having a yoke, a bracket and a pressure screw reacting in one direction against the bracket and in the opposite direction against the yoke, substantially as described.
9. In a plumbing fixture, the combination 35 of a bowl having an opening, a pipe, the end of which extends into said opening so as to form a slip-joint with the bowl, said pipe having near its end a lateral bend, a gasket surrounding the pipe, a follower having a 40 ring surrounding the pipe and engaging the gasket and having a yoke straddling the bend of the pipe, a pressure screw engaging said yoke and a bracket against which the pressure screw reacts, substantially as de- 45 scribed.
10. In a plumbing fixture, the combination of a bowl having vertical openings at top and bottom, pipes, the ends of which extend upward and downward and occupy said 50 openings, respectively, gaskets surrounding the pipes and contacting with the bowl, followers engaging said gaskets, respectively, and means for forcing the followers toward the bowl and thereby compressing the gas- 55 kets, substantially as described.
